J. Richards.

Elevated Railway

Patented Mar. 9, 1832.

March 9, 1832

Federick Richards Ellbridge, New York

Letters Patent

The Schedule referred to in these Letters Patent and making part of the same containing a description of the lands of the said Federick Richards, heretofore of this incorporated in said map and in the said description and wherein:

To wit it is known that of Federick Richards, of Ellbridge in the County of Saratoga and State of New York, has made an improvement in Rail ways and in the Cars or Carriages used thereon which is described as follows.

The Rail way consists of one Rail supported by post bents, or uprights placed at convenient distances apart and braced by diagonal braces extending from the rail to the top of the bar which supports the Rail and which is made to project over on one side of the supports so that when the weight suspended below is hung in the center, the iron bar or bar is turned on the top of the wooden rail before mentioned, on which the base of the car is to turn. The Car is made as follows. The wheel is about two feet in diameter made of steel iron or any suitable material. On the inner and edge of this wheel is cast or turned a groove to receive and work on the iron bar on the Rail before mentioned. These wheels are connected together by a post or bar in this bar are placed two braces to receive the quarter turn of the wheels, one on each side and for this purpose slots or openings are cut at the ends of the post in which the braces are put and in which they turn. The weight to be removed or carried is suspended from rods attached to the post or bar of the wheels and bent at right angles below the rail so as to clear it. Sufficient length is given to the bent arm to place a ring in the centre in a line with the wheel of the bar to which the weight is suspended. The arm is then bent up towards the rail forming a triangle. The body or weight to be moved is suspended to the iron rods by the rings in the centre below the rail. The bar is then moved along the rail. This Rail way may be made with two rods in this case there must be double posts or bents with braces, &c. the supports

even on each side sufficiently far to let the load pass the rails being supported by strong posts the purpose. This carriage and caries calculated to an load itself, and common heavy freight, also for travelling. When used for this purpose the carriage is to be filled up for accommodating my common number of passengers and suspended below the wheels and rail.

What I claim as my invention and desire to cover by Letters Patent is the before described improvement in rail ways and in the carriage or carriages used thereon. For further illustration of my invention I refer to the model and drawing of the same deposited in the Patent Office the testimony whereof I have hereunto subjoined say witness this 9th day of March 1832
